(57) **CLAIM**

The ornamental design for a laundry fur remover, as shown and described.

DESCRIPTION

FIG. 1 is a first side view of a laundry fur remover;

FIG. 2 is a first end view thereof;

FIG. 3 is a second end view thereof;

FIG. 4 is a second side view thereof;

FIG. 5 is a first cross-sectional view thereof along Section 5-5 of FIG. 4; and,

FIG. 6 is a second cross-sectional view thereof along Section 6-6 of FIG. 4.

The thin solid lines in the views have been provided for the purpose of illustrating the contour of the surfaces of the laundry fur remover. The cross-hatching of FIGS. 5 and 6 has been provided for the purpose of illustrating a cross-sectional view and forms no part of the claimed design. The dash-dot lines illustrate the location from which the section drawings are created and shown in FIGS. 5 and 6. The dash-dot lines form no part of the claimed design.
